REFRIGERATION

Albert R. Thomas, Evansville, Ind., assignor to
Servel, Inc., New York, N. Y., a corporation of
Delaware

Application December 18, 1936, Serial No. 116,489

6 Claims. (Cl. 62—119.5)

This invention relates to refrigeration and more particularly to a refrigeration system making use of evaporation of refrigerant in the presence of an inert gas.

5 It is an object of the invention to provide improved circulation and gas and liquid contact in refrigeration apparatus as will appear from the following description and accompanying drawing in which the single figure shows more or less 10 diagrammatically a refrigeration system embodying the invention.

Referring to the drawing, the system is made up of a number of steel vessels and pipes welded together to form a hermetically sealed system.

15 All spaces of the system are in open and unrestricted communication so that all parts are at the same total pressure. The system contains hydrogen and a water solution of ammonia. Other suitable alternative fluids may be used.

20 A vertical conduit 10 is connected at its lower end to the outer passage 11 of a liquid heat exchanger 12. The upper end of conduit 10 is provided with heat radiation fins 13 for air cooling. Alongside of the vertical conduit 10 is a narrower 25 riser 14. The lower part of the riser 14 is formed as a coil 15. The lower end of the coil 15 is connected to the inner passage 16 of the liquid heat exchanger 12, and the upper end of the riser 14 is connected to the vertical conduit 10 at a 30 point just below the heat radiation fins 13. The coil 15 is heated, as by a burner 17. The lower part of the vertical conduit 10 may also be heated by the burner 17. The internal cross-section of the riser 14 and the coil 15 is sufficiently small 35 that gas and liquid cannot pass each other therein (disregarding surface film) so that vapor formed by heating of liquid in the coil 15 becomes trapped in the liquid and causes liquid to rise through the riser 14 into the vertical conduit 10.

40 The lower part of the vertical conduit 10 may be referred to as a generator, or the lower part of the conduit 10, the coil 15, and the riser 14 may be collectively referred to as a generator.

In the generator, ammonia vapor is expelled 45 by heat out of the water solution. The vapor rises into the upper end of the vertical conduit 10 provided with the air cooled fins 13. This part of the vertical conduit 10 may be referred to as a rectifier. Here water vapor having a 50 higher condensation temperature than ammonia vapor is condensed out and flows back into the generator.

An evaporator 18 comprises a pipe coil constructed and arranged so that liquid entering the 55 upper end flows downward and is distributed

throughout the length of the coil. The rectifier 13 is connected to one end of a condenser 19. The other end of the condenser is connected to the upper end of the evaporator 18. Ammonia vapor flows from the rectifier 13 into the condenser 19 where it is condensed to liquid. The condensed ammonia drains from the condenser into the upper end of the evaporator 18 and flows downward therein in the presence of hydrogen which flows upward through the evaporator 18. 10 The liquid ammonia evaporates and diffuses into the hydrogen producing refrigeration effect.

15 The upper end of the evaporator coil 18 is connected by a conduit 20 to the inner passage 21 of a gas heat exchanger 22. The lower end of 15 the inner passage 21 is connected by a conduit 23 to a sump vessel 24. The lower end of the evaporator 18 is connected to the upper end of the outer passage 25 of the gas heat exchanger 22. The lower end of the outer passage 25 is 20 connected by a conduit 26 to a vessel 27. The lower part of vessel 27 is connected by a downwardly looped conduit 28 to the lower part of a vessel 29. A substantially horizontal conduit 30 25 has one end connected to the vessel 29 and the other end connected to the vessel 24. The conduit 30 is provided on its exterior with heat radiation fins 31 and on the interior is provided with baffles 32.

The lower part of vessel 24 is connected by a 30 conduit 33 to the inner passage 16 of the liquid heat exchanger 12. The outer passage 11 of the liquid heat exchanger 12 is connected by a conduit 34 to a circulation vessel 35 located above the vessel 27 but slightly below the level of the 35 point at which the riser 14 discharges into the vertical conduit 10 of the generator. The bottom of the vessel 35 is connected by a downcomer 36 to the vessel 27. The downcomer 36 extends into the vessel 27 and is open at its lower end therein. 40 The downcomer 36 is provided with heat radiation fins 37 and its internal diameter is sufficiently small that gas and liquid cannot pass each other therein so that liquid entering this conduit will trap beneath it any gas which is in the 45 conduit.

The upper part of vessel 29 is connected by a conduit 38 to the upper part of the vessel 35. The conduit 34 may be provided with heat radiation fins 39 for air cooling of liquid in this conduit. There is also provided a small liquid trap drain conduit 40 for conducting excess liquid from the lower end of the evaporator coil 18 into the inner passage 21 of the gas heat exchanger 22.

The operation of the system is as follows:

Rich gas, formed by evaporation of ammonia into hydrogen in the evaporator 18 as previously described, flows from the upper end of the evaporator 18 through conduit 20, inner passage 21 of the gas heat exchanger 22, and conduit 23 into the absorber sump vessel 24. The gas then flows through conduit 30 into vessel 29 and thence through conduit 38 into the circulation vessel

10 35. Liquid is delivered into the circulation vessel 35 through conduit 34 and drops downward through conduit 36 into the lower vessel 27. The liquid descending through conduit 36 carries with it gas and vapor which becomes trapped below 15 the liquid so that gas and vapor is drawn into vessel 35 from conduit 38 and discharged into the lower vessel 27 whence the gas returns through conduit 26 and outer passage 25 of the gas heat exchanger 22 to the lower end of the evaporator 20 18.

Liquid which is discharged into the vertical conduit 10 of the generator accumulates in the U-trap formed by the vertical conduit 10, outer passage 11 of the liquid heat exchanger 12, and 25 conduit 34, until the surface level of liquid in this U-trap reaches the point of overflow from conduit 34 into the circulation vessel 35. The liquid which flows downward through conduit 36 collects in vessels 27 and 29, the horizontal conduit 30, and vessel 24 until it reaches a surface level sufficient to form a column of liquid which balances the lighter column of liquid and gas in the generator coil 15 and riser 14. Liquid flows from the absorber sump vessel 24 through conduit 33 35 and the inner passage 16 of the liquid heat exchanger 12 back to the generator coil 15 from where it is lifted through riser 14 into the vertical conduit 10 as previously described.

Due to the expulsion of ammonia vapor from 40 solution in the generator, the liquid which overflows through conduit 34 into the circulation vessel 35 is referred to as weak or weakened absorption solution. The weakened absorption solution is brought into contact with gas during descent 45 through conduit 36 and is again brought into contact with gas in the horizontal conduit 30. The weakened absorption liquid in contact with the gas absorbs ammonia vapor out of the gas and becomes enriched so that the liquid which 50 flows from the absorber sump 24 through conduit 33 back toward the generator is referred to as strong or enriched solution.

Gas flowing from the evaporator 18 through conduit 20 toward the absorber vessel 24 contains 55 a relatively high concentration of ammonia vapor and this gas is referred to as strong or rich gas. The rich gas passing first through conduit 30 in contact with solution is deprived of some of its ammonia vapor. It then comes into further contact with absorption solution in the downcomer or fall-tube 36 where it is deprived of a further amount of ammonia vapor before returning to the evaporator. Thus, the gas returning to the evaporator is referred to as poor or weak gas.

60 65 In the circulation of fluids described above, the strong gas comes into contact first with strong solution in the horizontal conduit 30 and the resulting weaker gas then comes into contact with weakened absorption solution in the downcomer 36. The heat of absorption is dissipated to air by the heat radiation fins 31 and 37 on conduits 30 and 36 respectively. Other cooling media for these conduits may be provided. The amount of solution placed in the system is sufficient so that the surface level of liquid in conduit

30 is at least up to the upper parts of the baffles 32 in the horizontal conduit 30, so that gas passing through this conduit must bubble through the liquid beneath these baffles thus bringing the gas and liquid into intimate contact. The previously described circulation arrangement provides the necessary force for causing this bubbling of gas through liquid without any mechanical moving parts such as fan, blower, or injector and without any unbalanced liquid columns. 10

Let us assume that the relative circulation of liquid is about 10 kilograms of weak solution for each kilogram of ammonia evaporated in the evaporator 18 and the circulation of gas is about 3 kilograms of weak gas per kilogram of ammonia evaporated. The ratio of weak gas volume to weak liquid volume is then about 20 to 1. If, for example, the downcomer 36 is 21 inches long, a one inch slug of liquid falling through the length of conduit 36 would trap 20 volumes of weak gas 15 and carry this gas out of conduit 36 to a pressure equal to 1 inch of liquid. This is sufficient to bubble the gas through, for instance, one half an inch of liquid in the absorber conduit 30 and 20 make available another one half inch of liquid pressure to overcome resistance in the gas circuit.

The drawing shows the system more or less diagrammatically and it will be understood that various alterations may be made in the parts of 30 the apparatus shown and additions made within the scope of the invention. For examples: The evaporator 18 may be constructed as described in U. S. Patent 2,008,343 or U. S. Patent 2,057,408; the conduit from the condenser 19 to the evaporator 18 may be formed to provide a liquid seal as described in U. S. Patent 1,620,843, and provided with a condenser gas vent conduit as shown in U. S. Patent 1,645,706; there may be provided a hydrogen reserve vessel or pressure vessel as described in U. S. Patent 1,822,224; the generator 40 may be a vertical type as described in U. S. Patent 1,645,706, or it may be a horizontal type as described in U. S. Patent 1,830,302; various known rectifiers and analyzers may be provided.

It will be understood by those skilled in the art 45 that various other changes and modifications may be made within the scope of the invention which is not limited to the embodiment shown in the drawing and described in the specification, but only as indicated in the following claims. 50

What is claimed is:

1. In a refrigeration system of the kind employing an inert gas for equalizing pressure, members providing a circuit for inert gas including an evaporator and an absorber, means to supply liquid to said circuit in such quantity as to block off free flow of gas in the circuit and provide a body of liquid such that for gas to flow through the circuit it must flow through the body of blocking liquid, and a narrow drop tube in said circuit supplied at the top with liquid and gas for trapping gas by liquid and providing a gas propelling liquid weight, said drop tube being of such cross-section that liquid dropped therein bridges the tube from wall to wall and being of a height to provide a force for the circulation of the inert gas sufficiently greater than pipe resistance in the circuit to cause the gas to flow through the body of blocking liquid and circulate in said circuit, and means to supply liquid to the drop tube. 55

2. In a refrigerating system of the kind employing an inert gas for equalizing pressure, members providing a circuit for inert gas including an evaporator and absorber situated be- 60

- low the evaporator, a generator, and means to circulate absorption liquid between the generator and the absorber, the absorber including a vessel adapted to hold a body of absorption liquid
5. having a plurality of segregated surface levels and formed to block off free flow of gas in the inert gas circuit so that inert gas must pass below the liquid surface and through the body of liquid to flow from the space above one surface level to
- 10 the space above another surface level, and means within the system to develop sufficient force to circulate the inert gas in the gas circuit and cause the inert gas to pass into and by liquid displacement force its way through the body of
- 15 liquid in the absorber from the space above one surface level to the space above another surface level.
3. In an absorption refrigeration system of the kind employing an inert gas, members providing
- 20 a circuit for inert gas including an evaporator and an absorber situated below the evaporator and a circuit for absorption liquid including the absorber and a generator, and the absorber including a horizontal conduit arranged to hold
- 25 liquid in a quantity sufficient to block off free flow of gas in the inert gas circuit, means to circulate absorption liquid between the generator and the absorber and cause flow of liquid in one direction in the horizontal conduit, and means to
- 30 circulate inert gas in the gas circuit and cause the inert gas to pass into and by liquid displacement force its way through liquid in the horizontal conduit in a direction opposite to the flow of absorption liquid, said last-mentioned
- 35 means being operative by circulation of fluid in the system.
4. In a refrigerating system employing inert
- gas and including an inert gas circuit, means to supply absorption liquid in the circuit in such quantity as to block off free flow of gas in the circuit, said liquid blocking portion of said circuit being constructed and arranged to provide
- 5 a plurality of partially segregated pools of liquid disposed substantially horizontally with respect to each other, and structure embodied in the system to cause the inert gas to circulate in the gas circuit and bubble in said partially segregated
- 10 pools of liquid to force its way through the blocking liquid, thereby agitating the blocking absorption liquid at the liquid surface level.
5. In an absorption refrigeration system of the kind employing an inert gas, a circuit for inert
- 15 gas including an evaporator and an absorber, a circuit for absorption liquid including said absorber, said absorber including a conduit located substantially in a horizontal plane and arranged to hold liquid in a quantity that blocks free flow
- 20 of gas therein whereby gas flowing in said gas circuit has to pass through liquid in said liquid circuit by bubbling through liquid with the absorber in a generally horizontal direction, means to cause flow of liquid in said liquid circuit, and
- 25 means to cause flow of gas in said gas circuit and supplying sufficient pressure to cause gas to pass into and by liquid displacement force its way through liquid in the generally horizontal conduit of said absorber.
6. An absorption refrigeration system as set forth in claim 5 in which said last means is a fall tube gas pump constructed and arranged to be operated by a liquid in said liquid circuit and in a manner such that a small quantity of liquid
- 30 causes flow of a large volume of gas.

ALBERT R. THOMAS.

CERTIFICATE OF CORRECTION.

Patent No. 2,229,687.

January 28, 1941.

ALBERT R. THOMAS.

It is hereby certified that error appears in the printed specification of the above numbered patent requiring correction as follows: Page 2, second column, line 43, for the patent number "1,830,302" read --1,830,203--; and that the said Letters Patent should be read with this correction therein that the same may conform to the record of the case in the Patent Office.

Signed and sealed this 4th day of March, A. D. 1941.

Henry Van Arsdale,

(Seal)

Acting Commissioner of Patents.
